UNITED STATES PATENT OFFICE.

ANNA L. GROSS, OF PHILADELPHIA, PENNSYLVANIA.

COMPACT RETAINER.

Application filed February 28, 1927. Serial No. 171,557.

The object of this invention is to devise a novel construction and arrangement of a compact retainer whereby the conventional compact can be detachably connected with 5 the strap of a wrist watch or to any desired portion of the clothes of the wearer so that it will not be necessary for women to carry a bag to contain their vanity appliances.

It further comprehends a novel construction and arrangement of a retainer secured to one of the casing members of the compact, and provided with a clamping member that will clamp against the strap of a 10 wrist watch.

It further comprehends a novel construction of a compact retainer having releasing means which can be readily actuated by the right hand of a person to unclamp the clamping member of the compact retainer 15 which is in engagement with the strap of the wrist watch which is usually carried on the left hand wrist.

Other novel features of construction and advantage will hereinafter more clearly appear.

For the purpose of illustrating the invention I have shown in the accompanying drawing typical embodiments of it which in practice will give satisfactory and reliable 30 results. It is, however, to be understood that the various instrumentalities of which my invention consists can be variously arranged and organized and my invention is not limited to the exact arrangement and organizations of these instrumentalities, as 35 herein set forth.

Figure 1 is a perspective view showing a compact retainer embodying my invention in assembled position with the strap of a 40 wrist watch, which latter is in position on a wrist.

Figure 2 is a side elevation of a compact and its retainer, in an assembled condition with respect to the strap of a wrist watch, 45 the strap being shown in section.

Figure 3 is a rear elevation of a compact and retainer with the clamping member engaging the strap of the wrist watch.

Figure 4 is a plan view of the clamping 50 member, in detached position.

Figure 5 is a plan view of the releasing member, in detached position.

Figure 6 is a plan view of the clamping disc, in detached position.

55 Similar numerals indicate corresponding parts.

Referring to the drawings:—

1 designates a compact of any desired or conventional type, the casing of which consists of hinged sections secured together by 60 means of the usual fastening devices 2.

3 designates a spring disc which consists of a flat disc made of spring metal, or other resilient material having slits 4, extending through its periphery and forming a fixed portion 5 which is fixed by means of a fastening device 6 to the back of the compact 1. This fastening device 6 may consist of a spot-weld, rivet, solder or other fastening means. The slits 4 contribute on opposite 65 sides of the fixed portion 5 to form spring members 7, and connected with these members are the trunnion bearings 8, formed in any desired manner, and as illustrated by deflecting outwardly, a portion of the metal 70 or other flexible material of which the disc is made.

9 designates a clamping member having trunnions 10 adapted to be received in the trunnion bearings 8, and the clamping member 9 extends a desired distance beyond the trunnions 10 as indicated at 11 and is preferably rounded at its free end. The clamping member 9 forms a lever of substantial 75 width so that it will not cut into the wrist of the wearer and its outward end terminates in proximity to the periphery of the disc 3.

In order that the clamping member 9, when in clamping position may be readily 90 released, I provide a releasing member 12 which may be dispensed within some case arising in practice. This releasing member 12 is provided with a hinge 13 which is secured to the disc 3 in any desired manner. The releasing member 12 at its inner end, 95 is provided with an elongated flat bearing portion 14 and at its opposite end it is preferably rounded as indicated at 15 in order to form a grasping handle. The elongated 100 portion 14 is disposed beneath the free end of the clamping member 9 as will be understood by referring to Figure 3.

16 designates a wrist watch which is secured around the wrist 17 by means of the 105 conventional strap 19.

A wrist watch is commonly worn on the back of the wrist of the left hand and the strap encircles the wrist. In accordance with my invention, the compact is detachably secured to the strap at the front of the 110 wrist, so that, in case a woman desires to use

the compact, all that it is necessary to do is to raise the left arm and release the catch 2 and the articles contained within the compact are readily accessible for use.

5 Having thus described my invention what I claim as new and desire to secure by Letters Patent, is:—

1. The combination with the casing of a compact, of a disc of spring material having 10 slits opening through its periphery to form spring members and a portion fixed to said compact, and a clamping lever fulcrumed on said disc and retained in clamped position by said spring members.

15 2. The combination with the casing of a compact, of a disc of spring material having slits opening through its periphery to form spring members and a portion fixed to

said compact, and a clamping lever fulcrumed on said disc and retained in clamped 20 position by said spring members, and means to release said clamping member.

3. The combination with the casing of a compact, of a disc made of spring metal having a pair of spaced slits extending outwardly and opening through its periphery to form a fixed portion, the portions adjoining said slits being outwardly deflected to form trunnion bearings, means to secure said fixed portion to the compact casing and a substantially flat clamping member having trunnions to enter said trunnion bearings, and having an extension extending beyond said bearings and adapted to bear on the fixed portion of said disc.

ANNA L. GROSS.
